UNITED STATES PATENT OFFICE.

LOUIS JARVIS FAY, OF WATTS, CALIFORNIA.

SAFETY-RAZOR.

1,232,519.

Specification of Letters Patent. Patented July 10, 1917.

Application filed July 31, 1915. Serial No. 43,037.

To all whom it may concern:

Be it known that I, LOUIS JARVIS FAY, a citizen of the United States, and a resident of Watts, in the county of Los Angeles, 5 State of California, have invented certain new and useful Improvements in a Safety-Razor, of which the following is a specification.

This invention is an improvement in 10 safety razors and consists in certain novel constructions and combinations of parts as will be hereinafter described and claimed.

In the drawing forming a part of these specifications,

15 Figure 1 is a side view of the blade holder;

Fig. 2 is a longitudinal view of the blade compressor;

20 Fig. 3 is a longitudinal section of the guard;

Fig. 4 is a plan of the guard plate;

Fig. 5 is an end view of the blade holder;

Fig. 6 is a bottom plan of the blade holder;

25 Fig. 7 is a view of the blade;

Figs. 8 and 9 are longitudinal sections of a razor embodying my invention, the blade being omitted for the sake of clearness of illustration, Fig. 8 showing the guard with 30 drawn and the compressor stem unscrewed exposing a large opening in the blade holder in which the blade is dropped automatically positioning itself. Fig. 9 shows the compressor stem screwed up against the blade 35 holder, showing how the blade may be clamped between the plate of the blade holder and the blade compressor stem where it is held firmly and independent of all other means; also is shown the guard re-

40 leased and by a spring forced up against the plate of the blade holder. It will be noticed that the blade is not held in position by the guard but by the compressor. Also that the guard is movable longitudinally 45 along the handle of the blade compressor and that it is independent of all other parts of the razor. That in operation the frame is not taken apart to insert or remove the blade, there being but two parts, the frame

50 and the blade, the blade capable of being inserted in and removed from the frame almost instantaneously and without special care, the opening for the blade being large and without clips, guides or grooves.

55 The object of the invention is to provide a safety razor that can be handled quickly

and without special care, in which the blade is held firmly and immovably and which can be cleaned off of lather and hair while using without either unscrewing or taking 60 apart, which is done in the following manner: The blade end is inserted in the water and the guard pumped up and down two or three times; this forces a stream of water over the edges of the blade and between the 65 guard teeth, cleansing the razor instantly, and thoroughly.

My razor as shown, comprises a blade holder A, a blade compressor B, a guard C, a coil spring D, a blade E.

In the drawing, Fig. 1 shows the holder A comprising a plate, A¹ provided at its extremities with ears, A² extending at right angles to the plate A¹ and engaging the bar A³ extending lengthwise of the plate A¹, 75 said bar A³ being spaced a distance A⁴ away from the plate A¹ and provided at its center with a shank A⁵ projecting from the bar, said shank A⁵ bar A³ and ears A² adapted to slide through the slot C⁶ in the 80 guard plate C³, Fig. 4, and into the tube C¹ of the guard holder C Fig. 9.

Said shank A⁵ being bored and internally threaded A⁶ to receive the screw B¹ externally threaded on the end of the blade compressor B, Fig. 2, which blade compressor B¹ screws through the threaded bore A⁶ in the shank A⁵, thereby compressing the blade E between the body plate A¹ and the end of the blade compressor B, thereby holding the 90 blade firmly in position.

Manifestly the razor may be used when in this form, that is to say, with the holder A the blade E placed in the slot A⁴, and the blade compressor B screwed up against the 95 blade, holding the same firmly in the holder.

The blade compressor B is provided with shoulder B² as a seat for the coil spring D, Figs. 8—9; also with stop shoulder B³, to engage end of guard C⁴, Fig. 8, when guard C 100 is withdrawn to insert blade E, Fig. 7, which is without perforations and preferably of the double edged type and provided with rounded corners E¹ to bring the cutting edge under the guard and shoulder E² adapted to engage the ears A² of the blade holder A when the blade is dropped in the large opening A⁴, Fig. 8.

The guard C, Figs. 3—4 is composed of a tube C¹ and made integral with a guard plate 110 C³ which is notched or toothed C⁵ and slotted C⁶ through the guard plate C³ and into the

tube C, the bar A³ shank A⁵ and ears A² of the blade holder A, sliding through this slot C⁶ and into the tube C¹ which is recessed with shoulder at C² to receive spring D, Fig. 8, which bears between the oppositely facing shoulders C² and B² of respectively the guard and the blade compressor so that the spring acts normally to press the guard to the position shown in Fig. 9 in which it closely overlies the blade.

Be it understood that I reserve the right to make the blade compressor a tube or solid, also to make the blade holder flat using a non-flexible blade and to make any other changes in the construction which will fall within the lines of my drawings or claims; also that I own United States Letters Patent No. 1063021 patented May twenty seventh, nineteen hundred and thirteen, and this improvement is an extension of my previous patent.

I claim

1. A safety razor as herein described, a blade holder having a plate, means for connecting said plate with a bar spaced from said plate, said bar having a shank bored and internally threaded, a thin blade, a blade compressor having an externally threaded end, engaging the threaded shank, a slotted guard with a tubular extension encircling and longitudinally slidable upon the blade

compressor and a coil spring within the extension surrounding a portion of the blade compressor and engaging a shoulder thereof and a shoulder of the extension.

35

2. The combination with a blade holder having a plate, a bar and shank sliding, through a guard, means for connecting said plate and bar, a blade compressor screwing into and through the shank of the blade holder, a guard having a slotted plate to co-operate with the bar and plate of the blade holder, a tubular portion encircling and movable longitudinally along the blade compressor and means to raise the guard and 40 tubular portion.

3. The combination with a blade, a blade holder having a plate, means for connecting said plate with a movable bar, a blade compressor for pressing a blade against the plate, a sleeve having at one end a guard, said sleeve and guard fitting over the blade compressor and independently movable longitudinally along the blade compressor, whereby movement of the sleeve moves the 50 guard, and means for automatically forcing said sleeve toward the plate.

55 LOUIS JARVIS FAY.
